[57] CLAIM

The ornamental design for a twist guide for metalworking in a rolling mill, as shown.

DESCRIPTION

FIG. 1 is an enlarged perspective view of a twist guide for metalworking in a rolling mill showing my new design;

FIG. 2 is a front elevational view thereof;

FIG. 3 is an end elevational view taken from the right of FIG. 2;

FIG. 4 is a top plan view thereof;

FIG. 5 is a rear elevational view thereof;

FIG. 6 is an end elevational view taken from the left of FIG. 2;

FIG. 7 is a bottom plan view thereof.
